VACUUM CAN CLOSING MACHINE

Willy Diezel, Mount Vernon, N. Y.

Application June 27, 1934, Serial No. 732,589

19 Claims. (Cl. 113—82)

This invention relates to machinery for closing, sealing or treating cans, containers, or the contents thereof, in a rarefied atmosphere or under "vacuum".

More particularly this invention refers to means conveying a plurality of objects, in rapid succession into and out of a rarefied atmosphere or vacuum and to the machinery incidental to such conveying.

10 A particular object of this invention relates to the method of and means for mechanically introducing cans in rapid succession into vacuum pockets, performing an operation thereon while in said pockets, and then releasing them from 15 the vacuum and from the pocket.

Another object of this invention relates to a vacuum chamber or a chamber containing a rarefied atmosphere, and means for introducing into said chamber from the outside, in rapid succession, objects to be treated therein without substantially disturbing the pressure balance in said chamber.

These and other objects will be more clearly understood from the following description and 25 drawings, which relate to one specific modification in which my invention may be performed and executed.

In said drawings:

Fig. 1 shows a top view of such an exemplary 30 machine.

Figs. 2 and 3 show bisected sectional elevations of said machine, the sections being taken along lines and in the direction marked by the respective numbers in Fig. 1.

35 Fig. 4 shows a detail top view of an exemplary seaming head accommodated in the vacuum chamber of my machine. (The direction of the view is indicated at 4—4 in Figs. 2 and 3.)

Fig. 5 shows an elevation of the lower part of 40 my machine. This view is taken in the direction indicated by the numeral 5 and arrows in Fig. 1.

Fig. 6 shows a sectioned detail of the means for removing objects from the vacuum pocket. This view is taken along the line and in the direction 45 of arrows identified by the numeral 6 in Fig. 1. The conveyor belt is omitted.

Fig. 7 shows some mechanical details actuating and steadyng the vacuum pockets during operation. This view is taken in a direction and 50 along a line indicated by the numeral 7 in Fig. 2.

Fig. 8 shows in a top view a section through the vacuum chamber, said section being viewed in the direction and along the line identified by numeral 8 in Figs. 2 and 3.

55 Fig. 9 shows in a schematic view the other

extreme positions of the lever system serving to feed articles into and to remove them from the vacuum chamber.

Fig. 10a shows in a detail section, similar to that of Fig. 2, a modification of the lateral closure 5 of the pockets of the valve.

Fig. 10b shows on a reduced scale, a top view of the conical outer valve ring of the arrangement of Fig. 10a.

Similar numerals refer to similar parts 10 throughout the various views.

In the exemplary showings of the drawings, there is a substantially circular gear housing 11, which is provided with an extension 12. From the said extension arises a column 13. From the 15 column 13 extends over the top of the machine, a duct 14 and from said duct the box 15 depends into the machine (into the valve chamber).

The parts aforementioned represent a stationary frame of my machine. The duct 14 supports 20 the driving shaft 21, which extends therefrom at 22 and is there suitably driven by gears or pulleys (not shown) as customary in this art.

Power is transmitted from the shafts 21 to the gear housing at a reduced speed. For that purpose a worm 23 mounted upon shaft 21 engages upon a worm wheel 24 mounted on a vertical shaft 25, which passes down into the extension 12 of the gear housing 11. Upon the lower end of shaft 25 is mounted a gear 26 which meshes 30 with a gear 27 mounted upon a vertical idler shaft 28 journaled in the gear housing. The upper end of shaft 28 is rotatably retained in a bracket 29 which is mounted upon a stand 30 arising upon the inside of housing 11. 35

Upon the idler shaft 28 is mounted on top of gear 27 a Geneva driver 31. By way of roller 32, the said Geneva driver is engaged upon the Geneva follower 33. The follower 33 is mounted upon an idler stud 34 which carries at its upper 40 end a gear pinion 35. The pinion 35 meshes upon a gear 36, which is coupled to the vacuum chamber as will be presently explained.

The gear 36 rests upon a thrust bearing 37 and idles around a riser 38. The said riser 38 45 represents a hollow mandrel which is secured in the stand 30 by the means of a nut 39; said nut draws a flange 40 on the circumference of mandrel 38 onto the horizontal top of stand 30. Therefore the mandrel 38 also represents a part 50 of the stationary frame of the machine. From the top of gear 36 extend upwardly teeth 41, and from a circular collar 42 arranged thereabove extend downwardly the teeth 43, teeth 41 and 43 being engaged upon each other in tooth-clutch 55

fashion. The collar 42 is mounted upon the flange 44 which forms part of and extends down from the bottom 46 of the valve 45. From the bottom 46 of the valve 45 a plurality of valve pockets 47 arise. These valve pockets are outwardly interconnected by partitions 48 and walls 156 forming a valve or body part which, together with bottom 46, forms the lower extension on the vacuum chamber.

10 The number of vacuum pockets 47, which are evenly spaced in a circle around mandrel 38, determines the number of positions of the machine which has been selected in this instance as ten. Accordingly Geneva driver and follower 31 and 15 33 and the gear connection of pinion 35 and gear 36 is designed to offer an intermittent movement of gear 36, and the valve coupled therewith, the valve being intermittently rotated by each revolution of shaft 28 through the angle to which adjacent vacuum pockets are displaced from each other.

15 It will be noted that the extension and flange 44 of the valve, the collar 42 and the gear 36 are rotative in unison around the mandrel 38, by way of a bushing 49 extending through all these parts. Owing to the clutch coupling between collar 42 and gear 36, the whole valve may be lifted off the gear 36 and bushing 49 for purposes of repairs or replacement, and the teeth 41 and 43 of the clutch are therefore preferably a multiple or unit fraction of, or the same in number as, the valve pockets 47. From the bottom 46 of the valve extends down a skirt 50, which closes upon but rotatably extends around the top edge of the gear housing 11. Around the upper ends of the valve pockets 47 extends a flange 51, above which extends the rest of the vacuum chamber, i. e.:

20 From the said flange 51 extends up the cylinder 52 forming a wall of the vacuum chamber. Upon one side the cylinder has an opening 53, which is sealed by a removable cover 54, and through which the operator may reach the parts accommodated in the vacuum chamber. Over 25 the top of the cylinder 52 extends the cover 55, which is rotatably arranged upon the box 15 and is spaced, relatively to the duct 14, by a strap 56 extending around the box 15. By the said strap 56, a pipe 57 (Fig. 1) connects to box 15 and sealedly opens thereupon. The pipe 57 connects to means rarefying the air in the chamber or producing a "vacuum" therein, e. g., vacuum pumps (not shown). The vacuum chamber includes therefore the stationary box 15 and 30 is confronted by the cover 55, the cylinder 52 and the flange 51; parts of the rotating valve proper, i. e. the space surrounded by interconnected vacuum pockets 47 and downwardly closed by the bottom 46 are normally rarefied together with the vacuum chamber proper and therefore sealed by suitable packing wherever reciprocating, oscillating or rotating parts extend from the interior of the enclosure to the outside or vice versa. Such packings are well known in the art 35 and are provided for at 61, sealing between the stationary mandrel 38 and the bottom 46; at one end of all vacuum pockets 47 at 62, where the pistons 71 vertically, slidably extend thereinto; at 63, where rack extensions 72 extend through the walls 156 between the pockets 47; at 64, where shoulder 73 of cover 55 rotatably extends around box 15; at 65, where shaft 74 extends upwardly from the box, is journaled at 75 therein, and connects by miter gears 76, 77, to the driving shaft 21; and at 66 where shaft 78 extends

through the upper end of mandrel 38 by way of a ball bearing 79 into the vacuum chamber and into the gear housing 80 of the seaming head 81.

The seaming head is stationarily mounted upon the upper end of the mandrel 38 and is constructed in accordance with the standards of the art of sealing cans. It will therefore not be necessary to give details as to its exact construction; suffice it to state that the said head operates upon the top of cans raised thereinto, 10 and seals said cans. The spinning drive necessary for such operation is provided by shaft 74, as connected by gears 82, 83, 84, etc. to the seaming head. The necessary vertical reciprocations to knock out the sealed cans are caused by an angle lever 85 connecting to the top of the seaming head on one end, mounted at fulcrum 86 upon box 15 and connecting by link 87 at the other end to a rod 88 vertically reciprocatably extending through the housing 80, near the side 20 where said housing is closed by a cover 89. Upon rod 88 is fixedly mounted a bracket 90 which carries a roller 91. Roller 91 travels in the groove of box cam 92 and rotation of the cam is brought about by the shaft 78, upon the end of which it is mounted. It will be noticed that the ends of shafts 74 and 78 are steadied upon each other by a ball bearing 93 interposed therebetween. But otherwise they rotate independent of each other. The cam 92 is driven from the gear 30 housing, by means of gearing 95, 27 connecting the respective shaft 78 and the idler shaft 28.

25 Shaft 78 propagates rotation by way of gears 106, 105 to the cam 102 on bushing 101 upon the stationary vertical rod 103. The rod 103 is mounted upon the bottom of gear housing 11, is steadied by a bracket 104 mounted upon the side of the stand 30 and extends above said stand for purposes which will hereinafter be explained in detail. It will be noted that gears 105 and 40 106 are of like diameters as are gears 95 and 27, so that the cams 92 and 102 rotate at the same speed as the Geneva driver 31. In other words, the cams 92 and 102 will actuate the parts controlled thereby cyclically, each time the valve 45 is advanced one position. The cam 102 controls the rod 107 which is vertically reciprocatingly disposed in the gear housing 11 (see Figs. 2 and 7). For that purpose the bracket 108 and rod 107 are engaged upon cam 102 by way of roller 50 109. Upon an upper extension of bracket 108 is mounted another bracket 110 which is vertically slidably disposed upon the upper free end of rod 103. From the upper end of bracket 110 extends the key or catch 111.

55 The cam 102 is shaped so that it raises and lowers the parts controlled thereby each time there is an intermission in the Geneva motion imparted to the valve. The key or catch 111 will therefore be raised in those intervals into engagement between the evenly spaced teeth 112 provided upon the circumference of collar 42. The cuts between the teeth 112 correspond to the number of vacuum pockets 47, and the engagement of key 111 between adjoining teeth 112 serves to steady the valve in successive positions and also serves accurately to locate it relatively to the seaming head 81.

60 Upon the inside of the gear housing 11, near the top thereof, is mounted an internal box cam 113. The said box cam has a high and low position which are connected by substantially symmetrical spirals within the circle of the gear housing and its continuity is interrupted for a short 75

distance at its highest point, where the lug 114 fits thereinto.

The lug 114 is slidably accommodated upon the threaded upper part 115, of rod 107. Upon the part 115 are accommodated the nuts 116, which provide for vertical adjustment of lug 114 upon stud or rod 107. The lug 114 is provided with a recess 117 upon one side thereof, which matches with the continuity of the groove of the internal box cam 113, and which is in alignment therewith, when rod 107 is in its lowest position.

It will be noted that the shaft 107 is not fixedly mounted in the bracket 108, but that the said shaft 107 may vertically float against the pressure of spring 118, the tension of said spring being subject to adjustment by the threaded part 119 in bracket 108.

From the pistons 71, which are vertically slidably accommodated in the valve pockets 47, extend down the piston rods 120. At their lower ends these rods are provided with lugs 121 from which extend the rollers 122 into the cylindrical cam 113. The lugs 121 are shaped on one side 123 so that they slidably abut upon the upper and lower faces 124 of box cam 113. The angular positions of the pistons are thus defined, said faces 123 being always turned away from mandrel 38.

The rollers 122 will therefore always slide into the groove 117 of lug 114, as the valve pockets successively come into alignment with the seaming head 81. It will also be noted from Fig. 1, that the positions at which the machine is charged and discharged, i. e., cans are inserted into the vacuum pockets 47 and are withdrawn therefrom, are on the side of the machine opposite to the seaming head. At the said charge and discharge positions, the pistons 71 are in their lowest positions because the internal box cam 113 is lowest at that point. While the valve rotates, the pistons 71 are raised in the respective pockets until the rollers 122 slide into lug 114 at the highest position of internal box cam 113, when said pistons come into alignment with seaming head 81.

As mentioned before, the rod 107 is raised and lowered in the intervals between the Geneva movements. The pistons 71 engaged by lug 114, will therefore be raised and lowered, and the can standing on top of said piston will be brought into operative engagement with the seaming head in the manner of the commonly known operation of sealing under vacuum. In order to come into operative engagement with the seaming head, the cans have to emerge from the top of the vacuum pocket. This emerging is caused by way of lug 114 by the cam 102. However, while the valve rotates, and in all its stationary positions, except the position of alignment with the seaming head, the cans in the pockets 47 are below the top surface of the vacuum pockets which surface coincides with the surface 131 of flange 51.

Said surface 131 represents a smooth ring where the pockets issue therethrough. Into sealedly abutting slidable engagement upon said surface 131 extends a ring sector 132, which is pressed down by the tension of springs 133 engaged upon spider arms 134 extending from a semi-circular sleeve 135. The said sleeve 135 fits into a corresponding semi-circular cut out in the hub 136 which downwardly extends from the sealing housing 80. The remaining semi-circular hub and the semi-circular sleeve 135 face

each other at flanged extensions, said flanged extensions being fastened upon each other by bolts 137, so that the semi-circular sleeve 135 and hub 136 together form a split collar, by means of which the seaming head 81 as well as 5 the spider arms 134 are mounted upon the upper end of mandrel 38.

It will therefore be understood that the sector 132 is stationarily retained by the spider arms 134, sliding upon the surface 131 of the rotating 10 valve and upwardly closing all the vacuum pockets, except the ones facing and close to the seaming head. Thus the valve pocket 141 is upwardly open towards the vacuum chamber and the adjacent pockets 142 and 143 are similar but 15 only partly open in Fig. 8; whereas the rest of the pockets 142 and 143 and the seven other pockets—seven because I have provided for ten vacuum pockets in my example—are upwardly closed by the sector 132. 20

It will be noted that each vacuum valve pocket 47 is provided with a swinging door 151 where it faces outwardly. Each door is hinged below bottom 51 and upon the stud of the hinge is provided a pinion 152, so that by a rotation of 25 pinion 152, the door 151 may be swung from a closed position in which it depends vertically, into a substantially horizontal fully open position, in which such doors 153 and 154 are shown in the view of Fig. 1 and Fig. 8, and vice versa. The 30 oscillations of pinions 152 are brought about by racks 155 which are provided upon the ends of rods 72. Rods 72 slidably extend through the walls 156 above partitions 48 between the valve pockets. They carry lugs 157 and rollers 158 35 at their free ends, said lugs being slidably engaged upon the surface of cam 159; and the rollers 158 are engaged in the cam groove of said face cam 159.

The cam 159 is stationarily mounted upon the 40 outer circumference of the mandrel 38, for instance by a set screw 160. The groove 161 in cam 159 is concentrically disposed to the mandrel 38, close thereto, where the doors 151 are closed. But the said groove is looped outwardly and extends for a short distance farther away from the mandrel 38 on the side of the cam opposite to the seaming station where the doors are open, like doors 153 and 154. It will be understood that the doors 151 are provided with materials suitably sealing said doors around the lateral openings of the pockets 47 when said doors are closed, and the vacuum in said pockets pulls the said doors shut. 50

It will be seen from Fig. 8 that certain points 55 to the left and to the right of the seaming station, or of pocket 141, are connected to each other in pairs, by means of conduits 171 and 172. The said conduits are connected by suitable fittings, e. g., 173, to holes extending through ring sector 60 132, so that there is intercommunication between certain pockets to the left and to the right, although they are closed towards the outside—the door 151 being closed—as well as towards the vacuum chamber by means of the sector 132. 65

If in the view of Fig. 8, the valve revolves in a counter-clockwise direction, and presuming that conduits 171 and 172 were omitted, the valve pockets would be under atmospheric pressure from the time the door 151 is closed, until their 70 top emerges from below the sector 132, e. g., at the position of pocket 143. When a pocket emerges from under sector 132, it is evacuated, the atmosphere contained therein diffusing into the vacuum of the vacuum chamber, and the 75

atmosphere of said pocket would remain rarefied as the valve continues in its counter-clockwise rotation, although said pocket becomes shut off from the vacuum chamber as soon as it disappears underneath sector 132; and it would remain evacuated until the respective door is forced into the open position 153.

But by means of the interconnecting conduit 172, the vacuum in a pocket passing underneath the left end of said conduit will communicate to a pocket sliding underneath the right end of said conduit so that there is a pressure exchange and the air in the pocket passing below the right end of conduit 172 will become partly rarefied.

When the said pocket comes to communicate with the right end of conduit 171, atmosphere therein will be further rarefied by reason of inter-communication with a fully evacuated pocket just passing below the left end of the conduit 171.

It is thus understood that the air in the pockets passing towards the sealing head may be gradually rarefied before said pockets actually emerge from the sectors 132 and actually communicate with the vacuum chamber. At the same time pockets travelling towards the outlet at 153 are gradually filled with air; and at one point or the other, near the point of opening at the respective door, said pockets may readily be connected to the outside by means of another conduit 179 issuing upon such a pocket at such a point through sector 132, and issuing at the other end into a pocket open to the air.

From the foregoing it is clearly understood that a can inserted through the open door 154 into the respective pocket will become evacuated, will be sealed when it arrives at the position 141, and will then be returned to the open air and may then be withdrawn when the respective door is in the open position 153.

I now like to dwell shortly upon the means conveying a can through an open door 154 into a pocket and from an open door 153 out of a pocket.

An endless travelling conveyor belt extends past one side of the machine (Figs. 1, 5 and 8); the upper extent 181 of the conveyor belt travels in a manner known in this art to the left, and on its return it passes below to the right, where it is shown at 182. Cans 280 placed upon the top extent 181 of said belt, in the manner known to those acquainted with this art, will be conducted by guides 183 and 184 towards the machine, and are then pushed by a cyclically operated plunger 185 underneath the open door 154 into the respective valve pocket and onto the respective piston 71.

The plunger 185 is slidably disposed in a bracket 186, said plunger cyclically reciprocating in a direction radial in respect to the center of the machine. Upon the reciprocating plunger 185 engages a link 187 which is pivoted onto one free end of lever 188. The said lever is fulcrumed upon a bracket 189 which is mounted upon a housing 280 extending upon one side from the frame of the machine. A roller 190 mounted at the other end of said lever is engaged upon a groove disposed upon the bottom side of cam 191. The cam 191 rotates at the speed of the Geneva driver 131, said cam being connected with the gearing in the gear housing by means of the miter gears 201 and 202 issuing from shaft 25 at a certain level of column 13; the shaft 203 of miter 202 connects by way of helical gears 204 and 205 accommodated in housing 200 to the shaft 206 of the cam 191.

It will be noted that by means of suitable idler rollers 210, 211 and 212, mounted in housing 200, the conveyor belt is diverted on its top stretch from its top level 181, from the position at which it has delivered the cans through the open doors 154 into the pockets up to a position substantially in alignment with shaft 206. Intermediate to said positions, the plate 213 which serves as a cover to part of the housing 200, takes the place of and extends at the top level 181 of the endless belt. The said plate 213 slidably accommodates a slide 215 in a suitable track 214. The said slide 215 is engaged by the free end of a lever 221 which is fulcrumed at 222 upon the side of bracket 186. Intermediate its ends, the said lever 221 is connected by link 223 to the lever 188 so that lever 221 is also controlled by cam 191, and moves, more or less, in parallelism with lever 188.

In other words, when the plunger 185 pushes a new can through door 154 into the machine, the slide 215 is pushed underneath the door 153 close to the respective pocket, and a tensile member 231 extending from the top of slide 215 into the pocket slides onto the top of the can in the 25 pocket, or, at least extends thereover and prevents the can from being upset. The catch 232 is longitudinally tiltably fulcrumed in a recess below slide 215, and is normally tilted up at its right end (Fig. 6), due to its weight at the left 30 end. The catch is bevelled down to the right so that the nose at that end is pushed down underneath the can, when the slide 215 approaches the respective pocket 47. The piston 71 is spared out upon its top where the catch thus enters upon 35 the pocket 47, so that a clearance 220 is provided for the catch on top of the piston underneath the cam. The weight to the left of the catch causes it to swing back in counter-clockwise direction after the nose 233 has slipped underneath the 40 can so that then the hook provided behind the nose 233 engages underneath the rim ordinarily provided at bottom of a can and the can is withdrawn by said catch from the pocket 47 when the slide 215 moves back. As the slide 215 reaches the position farthest out from the machine, the catch 232 is tilted by a suitable lug 234 protruding between the tracks 214 into the path of the left end of catch 232; the catch thus releases the can, and the can is in a position substantially on top of a slot 235 which extends substantially parallel to the endless conveyor belt. The said slot 235 communicates with a channel 236 in the top of housing 200. In the said slot 236 is travellably disposed the upper extent of a 55 chain 241 which extends from a sprocket 242 mounted upon shaft 203 to an idler sprocket 243, which is mounted in housing 200. The said chain 241 is provided with suitable prongs 244 which extend up through the slot 235, when the 60 respective part of the chain travels through channel 236. A prong 244 engages upon the can released by the catch 232 on top of slot 235 and pushes said can between guides 251 and 252 on the plate 213 onto the endless conveyor belt 65 where the said belt returns over idler roller 212 to its top level position 181. From there the can is carried away and disposed of in the manner known to those acquainted with this art.

It is of course clear to those acquainted with 70 this art that—in analogy to doors 151—individual doors may be provided for to close the top of the valve pockets 47 instead of the plate 132. Conversely, in connection with the doors 151 a slide valve, may—in analogy to plate 132—re- 75

place the doors 151. Such a modification has been indicated in Figs. 10a and 10b.

It will be noticed that the outer flange 219 of the bottom 46 of the rarefied chamber has been omitted, as well as the skirt 50 extending down therefrom and encircling the gear housing 11. Instead thereof the housing 11 has been extended up at 261, and lugs 262 have been provided upon its outside near the top thereof, through which extend upwardly the adjusting screws 263. Upon these adjusting screws 263 rest the ears 264 extending at corresponding points from the outer rim of the base 265 of the conical slide ring 266.

15 The outer circumference of the interconnected valve pockets 47 of the valve 45 has been correspondingly developed outwardly, so that the lateral openings of the valve pockets 47 issue through a conical face 267 of the valve, which is 20 in suitable abutment upon the ring 266.

The ring 266 is exemplarily shown to extend around the complete machine (Fig. 10b), but at the loading and discharging points, i. e., at points corresponding to the doors 153 and 154 the conical inner face of ring 266 is perforated by an opening 268, which laterally extends over the openings of two adjacent valve pockets 47.

The adjusting screws 263 floatingly but non-rotatingly support the ring 266, so that the said ring may laterally adjust itself to hug the outer conical face 267 of the valve 45, the adjusting screws 263 serving to align the ring 266 at a suitable vertical level.

One of the adjusting screws 263, may engage 35 upon a lug 264 (e. g., in a radial slot 260) in such fashion that the ring 266 is substantially stationary during the operation of the machine and closes all but a few of the lateral openings of the valve pockets 47.

40 Although I have shown and described one form of embodiment of my invention in detail, yet I do not wish to be limited thereby, except as the state of the art and the appended claims may require, for it is obvious that various modifications and changes may be made in the form 45 of embodiment of my invention, without departing from the spirit and scope thereof.

What I claim is:

1. In a vacuum can closing machine a valve 50 containing a series of pockets each accommodating a can, means rotating said valve, a vacuum chamber rotative with said valve, a seaming head in said vacuum chamber, and means closing any one of said pockets towards said seaming head 55 in said vacuum chamber and towards the outside at predetermined positions, respectively.

2. In a vacuum can closing machine, a valve, containing a plurality of pockets for cans, a vacuum chamber made part of said valve and extending over and communicating with said 60 pockets, a cover in said vacuum chamber slidably abutting upon said valve and adapted to close the said pockets toward said chamber, pivoted doors on said pockets opening toward the outside, and means moving said valve and cover 65 relatively to each other and successively opening said doors and successively closing said opened doors.

3. In a vacuum can closing machine, a frame, 70 a valve rotating in said frame and comprising a series of pockets for cans, a vacuum chamber extending over said valve and said pockets and rotating therewith, a cover in said vacuum chamber slidably abutting upon said valve and successively closing said pockets towards said chamber 75

ber, a seaming head in said chamber facing any one of said pockets at a position in which said pocket is open towards said chamber, and means stationarily connecting said cover and said head with said frame.

4. In a vacuum can closing machine, a valve 5 with pockets extending therethrough and laterally opening therefrom, delivery means laterally facing one of said openings, a seaming head facing one of said pockets from the top, pistons vertically slidable in said pockets from a position registering with said means to a position in which a can deposited on said pistons is engaged by said head, a cam reciprocating said pistons, an intermediate stop on said cam for said pistons, 10 dan means for lifting of said pistons relatively to said cam at said intermediate stop, said means being adapted for adjustment in accordance with the height of the can.

5. In a vacuum can closing machine, a rotatable valve with a plurality of can pockets arranged in a circle, a vacuum chamber fixedly mounted upon said valve and extending over all of said pockets, and means for substantially complementarily closing each of said pockets towards said chamber and towards the outside at predetermined positions.

6. In a vacuum can closing machine of the type described, a valve with a plurality of can pockets arranged in a circle, ports radially opening from said pockets through the periphery of said valve, an individual door on each of said ports, and a mechanism for operating said doors in a cycle of predetermined rotation.

7. In a vacuum closing machine, a vertical stationary mandrel, a valve mounted to rotate on the stationary mandrel, said valve containing a plurality of can pockets opening to the top and to the sides of the valve, a vacuum chamber fixedly mounted on said valve and rotatable therewith and extending over all of said pocket openings in the top of said valve, a cover in the vacuum chamber non-rotatively mounted on the stationary mandrel and having a face abutting upon said valve in sliding relationship therewith to close to the vacuum chamber valve pockets in predetermined positions, means to rotate the valve and the vacuum chamber, and means to close the valve pocket openings to the outside of the valve at predetermined positions.

8. In a vacuum closing machine, a vertical stationary mandrel, a valve mounted to rotate on the stationary mandrel, said valve containing a plurality of can pockets opening to the top and to the sides of the valve, a vacuum chamber fixedly mounted on said valve and rotatable therewith and extending over all of said pocket openings in the top of said valve, a cover in the vacuum chamber non-rotatively mounted on the stationary mandrel and having a face abutting upon said valve in sliding relationship therewith to close to the vacuum chamber valve pockets in predetermined positions, means to rotate intermittently the valve and the vacuum chamber, and means to close the valve pocket openings to the outside of the valve at predetermined positions.

9. In a vacuum can closing machine, a rotat- 70 ing valve containing a plurality of pockets for cans, a vacuum chamber endwise facing all of said pockets, said valve pockets communicating with said chamber and the outside, a seaming head in said chamber, means in said chamber for closing said pockets towards said chamber at predetermined positions, means for outwardly 75

closing said pockets when they align with said seaming head, and a mechanism moving said means and head and said valve relatively to each other.

5 10. In a vacuum can closing machine, an intermittently rotating valve containing a plurality of pockets for cans, a vacuum chamber extending over all of said pockets and communicating and rotating therewith, a cover in said vacuum chamber slidably abutting upon said valve and for closing any one of said pockets toward said chamber, and means moving said valve and cover relatively to each other.

15 11. In a vacuum can closing machine, an intermittently rotating valve containing a plurality of pockets for cans, a vacuum chamber mounted upon said valve and extending over all of said pockets, a stationary cover in said vacuum chamber relatively slidably abutting upon said valve and closing one of said pockets toward said chamber, movable doors on said pockets opening toward the outside, supporting means on said machine for said cover, and means moving said valve and chamber and successively 20 opening said doors and successively closing said 25 opened doors.

12. In a vacuum can closing machine, a valve comprising a series of pockets for cans, a vacuum chamber extending from said valve over said 30 pockets, a cover in said vacuum chamber relatively slidably abutting upon said valve and closing one of said pockets toward said chamber, movable doors on said pockets opening toward the outside, and means moving said valve and chamber relatively to said cover and opening and closing the doors of said pockets when said pockets are closed by said cover.

13. In a vacuum can closing machine, a revolving vacuum chamber comprising a body part 40 with pockets having an opening directed onto the vacuum space of said chamber and a second opening towards the outside atmosphere, a cover slidable relatively to said body and closing said first opening, a door predeterminedly closing said 45 second opening, and a mechanism rotating said chamber, sliding said cover and body part relatively to each other, and controlling the opening and closing thereof and of said door.

14. In a vacuum can closing machine, a valve 50 containing a plurality of pockets each accommodating a can, a vacuum chamber mounted on said valve and communicating with all of said pockets, a plate for closing said pockets relatively to said chamber, a mechanism for moving said plate and 55 valve relatively to each other and for closing any one pocket to said vacuum chamber at predetermined positions, and means for closing any one pocket to the outside in predetermined positions while it is closed toward said vacuum chamber.

60 15. In a vacuum can closing machine, a frame,

a valve containing a series of pockets each accommodating a can, means rotating said valve on said frame, a vacuum chamber stationary relatively to said valve, a seaming head in said vacuum chamber, a plate closing any one pocket to 5 said vacuum chamber at predetermined positions, a mandrel non-rotatively engaging said plate on said frame, and another means closing the same pocket to the outside in predetermined positions.

16. In a vacuum can closing machine, a valve 10 containing a series of pockets each accommodating a can, means rotating said valve, a vacuum chamber stationary relatively to said valve, a seaming head in said vacuum chamber, a stationary plate slidable on said valve and adapted 15 for closing each of said pockets towards said vacuum chamber at predetermined positions, a mandrel arising in said machine and engaging and arresting said head and plate, and movable means closing any one of said pockets to the 20 outside in predetermined positions.

17. In a vacuum can closing machine, a valve with pockets receiving cans, pistons slideable in said pockets, means shifting said pistons from a bottom receiving position into an intermediary 25 evacuating position and from the intermediary position into a top seaming position, said means being adjustable,—for the purpose of accommodating cans of different height,—relatively to the movements of the pistons, such adjustment being however provided only between the intermediary evacuating position and the top seaming position.

18. In a vacuum can closing machine, a rotating valve comprising a plurality of pockets for 35 cans, a vacuum chamber superimposed upon said valve, a frame rotatably supporting said valve and chamber, a door mechanism for intermittently closing one of said pockets towards said chamber and for intermittently outwardly closing any two of said pockets, a seaming head in 40 said chamber operatively facing the can in said one pocket, a belt conveying said cans, and means feeding cans from said belt into one pocket and onto the belt from the other of said two pockets. 45

19. In a vacuum can closing machine, a valve with a plurality of can pockets arranged in a circle, a vacuum chamber fixedly mounted upon said valve and extending over all of said pockets, a seaming head inside of said vacuum chamber 50 and aligned with a point of said circle, means for substantially complementarily closing each of said pockets towards said chamber and towards the outside at predetermined positions relatively to said head, and means relatively rotatably supporting said head on one hand and said valve and chamber on the other hand, the axis of such rotation extending normal to the plane of said circle through the center of said circle.

WILLY DIEZEL. 60
